UNITED STATES PATENT OFFICE.

FREDERICK WILLIAM COX, OF TORONTO, CANADA.

FEEDING DEVICE FOR STEAM-STOKERS.

SPECIFICATION forming part of Letters Patent No. 663,867, dated December 18, 1900.

Application filed May 5, 1900. Serial No. 15,640. (No model.)

To all whom it may concern:

Be it known that I, FREDERICK WILLIAM COX, a subject of the Queen of Great Britain, residing at Toronto, in the county of York, 5 in the Province of Ontario, Canada, have invented certain new and useful Improvements in Feeding Devices for Steam-Stokers, of which the following is a specification.

My invention relates to improvements in feeding devices for steam-stokers; and the object of my invention is to design a simple and cheaply-constructed but durable feeding device for steam-stokers that can easily be operated by the attendant; and it consists, 15 essentially, of a suitable structure composed of a suitable number of hoppers constructed so that the coal can be conveniently and quickly discharged therefrom by means of gravity, suitable means being provided for 20 operating means in the discharging end of said hoppers, so as to permit the coal to flow from said hoppers or else to arrest the flow of coal therefrom, and other details of construction, as hereinafter more particularly 25 explained. It will of course be understood that the hoppers discharge the coal into the usual steam-operated stoker, as indicated in the drawings, which feeds the coal into the retorts.

30 Figure 1 is a general perspective view of my feeding device for steam-stokers, parts being broken away, showing the construction and operation of the same. Fig. 2 is a vertical section through the front portion of two 35 of the hoppers, showing the construction of the operating parts more fully.

In the drawings like letters of reference indicate corresponding parts in each figure.

A is the feeding device itself, which is divided into any suitable number of hoppers 40 B, C, and D. The said feeding device is preferably made of sheet-iron or sheet-steel and is supported upon any suitable base or platform by suitable supports E. Suitably secured to the walls F and F', as by rivets f, and at such an angle as to permit the speedy flow of coal thereover are the floors G of the several hoppers. The walls F and F' are provided with extending wings H, which extend 45 any suitable distance above the floors G and down the sides of their discharge ends. These

said extending wings prevent coal from falling from the sides of said discharging ends of said hoppers. Having suitable bearing at each end in the walls F and F', as at e, by their 55 bent ends I are bars J, to which are suitably secured any suitable number of teeth K, which operate in the elongated slots L, formed in the floors G and near their discharging ends. I preferably make the teeth or claws K tapered from base to top of tooth or claw, and also preferably make them curved. The said curved teeth or claws are preferably secured to the bars J, so that the whole curvature of each tooth can be for all intents and purposes 60 described as describing one and the same arc, concentric with the arc described by the said bars. These curved and tapered teeth I find when the bars J are being returned to normal position can be forced between the pieces of 65 coal much easier than if they were straight, as they shove upwardly and backwardly against the coal. Unrotatably secured on the ends I of the bars J, which are journaled in the wall F, are arms M, N, and O, which 70 are provided with handles o. Pivoted on the pin P, secured in the wall F, are a number of levers Q, R, and S, the operated ends of which are connected by rods T to the arms O, N, and M, respectively. On the ends I 75 of the bars J, which have bearing in the wall F', are secured arms U, provided with an adjustable weight u, as shown in dotted lines in Fig. 2. These said weighted arms are unrotatable and balance the movement 80 of the bars J, so that when the said bars are moved into a position they will remain in that position. Having bearing in the walls F and F', as shown at g, are a number of feeders V, which have rigidly secured to their outer ends, 85 having bearing in the wall F, ratchet-wheels W, which are operated by toothed levers Y, pivoted to the arms M, N, and O. These said toothed levers are held in contact with the ratchet-wheels W by the springs Z, secured 90 to the wall F. Suitably secured in front of the feeders V to the floor G of the hoppers C and D and extending for the whole length of said feeders are protecting-plates m. These 95 said protecting-plates prevent the coal from jamming against the feeders m, and so prevent them from rotating. The feeders V are 100

provided for their whole length with vanes *v*, which come in contact with the coal and gradually feed it toward the discharge end of the hopper.

5 It will of course be understood that I can construct the feeders *V* with teeth in place of the vanes *v* or in any other suitable manner for the purpose required.

Having now described the principal parts 10 of my invention, I shall describe its operation.

To feed coal into the stoker *n*, the lever *R* (we will take for illustration) is moved into the position shown in Fig. 1, moving the arm *N* upwardly, thus moving the bar *J* into the 15 position shown, thus moving the teeth or claws *K* out of the slots *L* and out of the path of movement of the coal in this hopper, so that the said coal will have an unobstructed flow therefrom into the stoker *n*. Simultaneously 20 the arm *N* is being moved upwardly, the lever *Y* is also moved upwardly, revolving the feeder *V'* by means of the ratchet-wheel *W'*. When sufficient coal has passed into the stoker, the arm *R* is returned to normal, 25 bringing the other parts before described back to normal. It will of course be understood that the levers *Q* and *S* and their connected parts operate in the same manner as the lever *R* and its connected parts before described. The hoppers *B*, *C*, and *D* are of 30 course filled from the top in the usual manner. I do not find it necessary in the hopper *B* to place a protecting-plate before the feeder therein, as the coal is not apt to jam the said 35 feeder, as its vanes *v* operate very close to the lower end of the front plate *B'* of the said hopper. The size of coal used will of course determine the closeness of the teeth or claws *K*. In case the attendant is not up high 40 enough to reach any of the levers *Q*, *R*, or *S* he can feed coal into the stoker by taking hold of the handle *o* of any of the arms *M*, *N*, or *O* and operate the mechanism, as before described, by moving the required arm upwardly. 45

In carrying out my invention it will of course be understood that I can use as many hoppers as required in constructing my feeding device.

50 From this specification it will be seen that my feeder is cheaply constructed, positive in action and easy to operate, and will not get out of order.

What I claim as my invention, and desire 55 to secure by Letters Patent, is—

1. A feeding device for stokers comprising a hopper constructed at the best angle to utilize gravity for convenient discharge of coal therefrom, supports for same, a suitable 60 counterbalanced bar journaled in the walls of said hopper and extending for the whole width of said hopper and operated underneath the discharging end thereof, suitable curved teeth secured in alinement to one another in said counterbalanced bar, the said teeth extending up through slots in said dis-

charging end into the path of movement of the coal in the hopper and operated for determining the quantity of coal discharged from said hopper, and suitable means for operating said counterbalanced bar and curved teeth secured thereto, as set forth and for the purpose specified. 70

2. A feeding device for stokers comprising a hopper constructed at the best angle to 75 utilize gravity for the convenient discharge of coal therefrom, supports for same, a suitable feeder having bearing in said hopper and situated a suitable distance above the floor of said hopper, means for revolving same, a suitable counterbalanced bar journaled in the walls of the hopper and extending for the whole width of said hopper and operated underneath the discharging end thereof, suitable curved teeth secured in alinement to one 80 another in said counterbalanced bar, the said teeth extending up through slots in said discharging end into the path of movement of the coal in the hopper and operated for determining the quantity of coal discharged 85 from said hopper, and suitable means for operating said counterbalanced bar and curved teeth secured thereto, as set forth and for the purpose specified. 90

3. In a device of the class described the combination with the hopper, floor thereof and slots therein, of the bar *J*, having bearing in said hopper, teeth secured to said bar, and means for operating said bar, as set forth and for the purpose specified. 95

4. In a device of the class described the combination with the hopper, floor thereof and slots therein, of the counterbalanced bars *J*, having bearing in said hopper, teeth so secured to said bar that they will describe an 100 arc concentric with the arc described by said bars, feeders *V*, having bearing in said hopper and constructed as described, means for operating said feeders *V*, and an arm attached to said bar *J*, for operating same, as 110 set forth and for the purpose specified.

5. In a device of the class described the combination with the hopper, floor thereof and slots therein, of the counterbalanced bar *J*, having bearing in said hopper and situated 115 underneath said floor, curved tapered teeth *K*, so secured to said bar that they will describe an arc concentric with the arc described by said bar, feeder *V*, having bearing in said hopper, and constructed as described, ratchet-wheel rigidly secured on one end of said feeder, toothed spring-held arm engaging with said ratchet-wheel, a lever pivoted near the top of said hopper and connected to an arm and operating same, said arm operating said 120 toothed spring-held arm and also being secured to the bar *J*, for operating the same, as set forth and for the purpose specified.

6. The combination, in a device of the class described, with the hopper, floor *G*, slots *L*, 125 counterbalanced bar *J*, provided with teeth *K*, as described, said bar being supported as 130

described, and described operating means for same, and feeders V, constructed, supported, and operated as described, of the protecting-
plates m, secured to the floors G, and extend-
ing so as to prevent the jamming of said
feeders by the coal, all arranged as set forth
and for the purpose specified.

In testimony whereof I have signed my
name to this specification in the presence of
two subscribing witnesses.

FREDERICK WILLIAM COX.
